CONTACT BREAKER OF IGNITION SYSTEMS
FOR INTERNAL-COMBUSTION ENGINESLucien Delorme, Paris, France, assignor to Societe
Anonyme dite: Etablissements Duceiller, Paris,
FranceApplication July 9, 1951, Serial No. 235,861
In France July 8, 1950

3 Claims. (Cl. 200—30)

1

This invention relates to ignition systems for internal combustion engines and more particularly to improvements in contact breakers mounted in the primary circuit of ignition systems, either of the H.-T. coil or magneto type, applicable more especially to those cases requiring a relatively high frequency of contact breaks, for example 20,000 per minute.

The chief trouble in designing a contact-breaker in view of obtaining such a high number of breaks is to obtain constant opening and closing time intervals and, above all, to avoid the bouncing effect generally produced at high speed when the contacts close.

This bouncing effect is caused by the impact of the movable contact against the fixed contact which brings about a momentary deformation of the arm carrying the movable contact on the one hand and of the member supporting the fixed contact on the other hand. Both parts resume their original position with a force depending on the inertia and speed of the arm at the instant in which the impact occurs. When this force exceeds that of the contact arm spring the contacts are opened. By increasing the speed the same phenomenon may occur several times during each closing period of the contact-breaker.

In the case of H.-T. coil or battery ignition the consequence of this bouncing effect is to reduce the time for setting up a current flow through the coil and therefore to step down its electrical energy. In the case of magneto ignition the bouncing effect set up in the contact-breaker may produce ill-timed ignition sparks.

One remedy to the drawbacks set forth hereabove is to reduce the inertia of the contact arm or increasing the spring pressure, but mechanical difficulties or an excessive wear in the contact-breakers militate against this solution.

Now, according to this invention, a satisfactory answer to this problem is obtained by interposing a rubber pad between the fixed contact and its supporting member. This rubber pad exerts a shock-absorbing action by damping out part of the energy spent in the closing impact and will resume its original position only at a relatively low speed. Then, the inertia of the contact arm is too low to overcome the pressure of the contact spring and any rebound is avoided. The mechanical efficiency of the contacts is improved and the noise substantially reduced.

The affixed drawings forming part of this specification illustrate diagrammatically by way of example one possible embodiment of the invention, with the understanding, however, that the

invention is not confined to any strict conformity with the showing of the drawings but may be changed or modified so long as such changes or modifications mark no material departure from the salient features of the invention as expressed in the appended claims.

In the drawings:

Fig. 1 is a plane view of the contact-breaker.

Fig. 2 is a fragmentary side view showing the fixed contact with its supporting member.

Fig. 3 is another fragmentary view of the fixed contact mounting.

Figs. 4 to 6 illustrate a practical embodiment of the invention wherein:

Fig. 4 is a plane view of the assembly;

Fig. 5 a side view of the fixed contact mounting, and

Fig. 6 an elevational view at a greater scale of the movable contact mounting.

Referring now to the drawings and firstly to the diagrammatical embodiment of Figs. 1-3, the engine-driven cam 1 actuates a contact-arm 2 through a cam-follower 3. The arm 2 carrying the movable contact 6 at its free end is pivotally mounted on a pin 4 and urged towards the cam 1 by a leaf spring 5. The movable contact 6 registers with a fixed contact 7 fast with a small plate 8.

A supporting member 9 is adjustably mounted on a plate 10. A rubber pad 11 is interposed between the small plate 8 and the supporting member 9 and cemented thereto through known methods. A strip 12 of flexible metal ensures the electric connection between contact 7 and support 9.

In the modified embodiment of Figs. 4-6 the fixed contact 7 is fast with an arm 8 covered completely with a sheath of elastic material such as rubber. This arm 8 passes across a rubber pad 11, in which it may be embedded by molding, so that the fixed contact is mounted in a resilient manner while being electrically insulated from its supporting member. Thus, the vibration of the fixed contact 7 is damped out in a satisfactory manner, particularly when it is struck by the

movable contact 6, so that the latter will be prevented from bouncing. The rubber pad 11 is carried by a U-shaped bracket in which it is clamped. In the construction shown, the rubber pad 11 is slightly compressed by the resilient force of a spring 5 acting upon the arm 2 carrying the movable contact so that when the contacts open the fixed contact 7 may follow to a certain extent the movable contact 6 whereby suitable

closing time conditions may be obtained.

Besides, when the contacts close the kinetic energy of the movable contact is absorbed by the rubber pad 11 and thus any tendency to bouncing is eliminated. In fact, the rubber material used as a support not only acts as a resilient member permitting a slight backward movement of the hitherto rigid fixed contact, but also as a vibration-absorbing dash pot. By way of example, it may be indicated that a rubber material having a Shore hardness of 50 ± 5 is the most suitable for the purpose specified.

In order to reduce the inertia of the arm 2 and therefore suppress the bouncing effect caused thereby, the cam-follower 3 is mounted separately from this arm at one end 16 of a lever 17 fulcrumed about a fixed pin 18 and operatively connected with its opposite end 19 to a push rod 20 fast with the movable centre of a diaphragm 21 subjected to a vacuum varying in direct ratio with the engine speed. Under the best ignition conditions, it is necessary that the engine acceleration and therefore the increase in current breaks per time unit be accompanied by a corresponding increase in the dwell, that is the ratio of the contact closing time to the total time of a cycle. For this purpose, the cam follower 3 is moved in a direction adapted to reduce the open contact time and therefore increase the closed contact time with the increasing R. P. M. value.

The suppression of the bouncing effect is promoted by the fact that the arm carrying the movable contact is fixed with a leaf spring 13 of the improved contact arm assembly of this invention. This spring 13 constantly bears against the suitably bent end of an arm 14, owing to the resilient pressure of an auxiliary spring 15. With this arrangement the conventional pivotal mounting of the contact arm which is a source of friction counteracted by a spring may be dispensed with. The assembly consisting of spring 13, counterspring 15 and arm 14 may be secured by means of a screw 22.

This reduction in the inertia of the contact arm and the suppression of the detrimental bouncing effect make it possible to reduce the contact pressure exerted by the spring 5 and therefore the pressure of the cam follower 3 on the cam 1, thereby lessening the risks of shivering the contact points at the impact and the wear of parts in frictional engagement.

The face of cam follower 3 which engages the contact arm 2 is slightly curved so as to work with, and distribute wear over its entire surface, taking into consideration the circular path described by the cam follower during its operation.

The opposite face of cam follower 3 engaging the cam face proper is wedge-shaped in order to

reduce to a minimum the lifting time, which is the open-contact time, of the cam follower 3 on each projection of cam 1.

What I claim is:

5. 1. A contact-breaker for ignition system comprising a supporting member, a rubber cushion carried by said supporting member, a fixed contact, an arm carrying said fixed contact, said arm passing through said rubber cushion without touching said supporting member, and a movable contact cooperating with said fixed contact.

2. A contact-breaker for engine ignition system comprising a supporting member, a rubber cushion carried by said supporting member, a fixed contact, an arm carrying said fixed contact, said arm passing through said rubber cushion without touching said supporting member, a rocking lever, a movable contact carried by said rocking lever and cooperating with said fixed contact, a rotary cam, a follower adapted to transmit the successive contact-breaking thrusts from said cam to said rocking lever, a pivotally mounted arm, means adapted to move said pivotally mounted arm in accordance with the conditions of operation of the engine, and a pin mounted on said pivotally mounted arm and adapted to act as a fulcrum to said follower between said cam and said rocking lever.

3. A contact-breaker for ignition system, comprising a supporting member, a rubber cushion carried by said supporting member, a fixed contact, an arm carrying said fixed contact, said arm passing through said rubber cushion without touching said supporting member, a movable contact cooperating with said fixed contact, a thin resilient blade having one stationary end and carrying said movable contact on the other end, a fixed bearing member mounted in the vicinity of said stationary end of said blade, a spring member adapted to urge said resilient blade against said bearing member, and another spring member acting upon said resilient blade between said fixed bearing member and said movable contact, and urging said elastic blade in a direction such as to cause said movable contact to engage said fixed contact.

LUCIEN DELORME.
